UNITED STATES PATENT OFFICE.

JOHN N. HAHN, OF CLEVELAND, OHIO.

METHOD OF REINFORCING A BOARD.

1,179,177.

Specification of Letters Patent. Patented Apr. 11, 1916.

Continuation of application Serial No. 12,887, filed March 8, 1915. This application filed September 17, 1915. Serial No. 51,292.

To all whom it may concern:

Be it known that I, JOHN N. HAHN, a citizen of the United States, residing at Cleveland, in the county of Cuyahoga and State of Ohio, have invented a new and useful Improvement in Methods of Reinforcing a Board, of which the following is a specification, the principle of the invention being herein explained and the best mode 5 in which I have contemplated applying that principle, so as to distinguish it from other inventions.

My invention pertains to a method of reinforcing board material whether of indeterminate or measured length prior to putting it to some manufacturing purpose. The idea, as feasibly exemplified in the drawings, comprises the affixing to, creasing and bending with an artificial piece of stock 10 of a metal member having prongs projecting therefrom. Preferably such prongs are struck-out and therefore integral tongues arranged according to some definite plan over the area of the member and all projecting in the same general direction. This allegedly novel conception of automatically affixing reinforcement continuously across a board is of record in my copending application Serial Number 12,887, filed March 8, 15 30 1915. This application is therefore a continuation of the earlier application just identified, as to all matter common to the two applications.

Accordingly, my method consists in automatically applying and since advisable also clenching a given length of strap-iron or other suitable metal area to a board preparatory to employing the same as a part of some finished industrial product or pack- 20 age. Preferably the procedure is continuous and progressively across or along the board. My invention effects a smooth continuity or stretched application of a flexible metal reinforcing strip of given length 25 preparatory to clenching upon a flexible paper or fiber board sheet of approximately like length. The advantages of neatness, firmness and strength are attained in a manner not possible where separate slats or 30 boards are so reinforced. When the strap-iron and board are both flexible, an association of the two after the manner of this invention enables simple manufacturing expedients to impart the desired conformation 35 to both at once by first creasing and then

scoring-up by bending. Furthermore, my method does not require the use of separate staples, nor manual driving of individual prongs whether of staples or of strap-iron. It does assure an equal extent of both materials between prongs by stretching and additionally bends over or upsets the prongs to effect a clenching and hold such relationship. 60

With the foregoing and other objects in view the invention consists of the novel combination of steps as hereinafter more specifically described and illustrated in the accompanying drawings, wherein is shown preferred and modified structural agencies, 65 but it is to be understood that changes, variations and modifications can be resorted to which come within the scope of the claims hereunto appended.

Figure I is a side elevation of a machine 70 adapted to perform my method. Fig. II is a top plan of one portion thereof. Fig. III is an enlarged broken detail showing two succeeding steps. Fig. IV is an enlarged section taken on line IV—IV of Fig. I. Fig. V is a plan of a piece of board material reinforced after the manner of my invention and also creased along predetermined lines. Fig. VI is a fragmentary section on line VI—VI of Fig. V. Fig. VII is an enlarged section taken through the middle of Fig. V. Fig. VIII is a similarly enlarged bottom plan of a portion of Fig. VII. Fig. IX is a perspective view of the board shown in Fig. V after the 80 same has been bent up as determined by the creases thereacross. Fig. X is a side elevation of a simplified modification for performing only the concluding operations. Fig. XI is an enlarged section on line XI— 90 XI of Fig. X. Fig. XII is a view corresponding to Fig. XI similarly enlarged and showing the reinforcing member itself reinforced. Fig. XIII is a view corresponding to Fig. V showing a reinforcing member of 100 different shape applied to a board.

Adverting now to the drawings in order to better understand the following description of the arrangement and operation thereof, it is stated at the outset that Fig. 105 I illustrates a mode of practising, as a continuous operation of a single machine, the steps required to fashion three metal strips M of indefinite length with metal prongs P and thereafter successively applying the 110

same along fiber board material B having a limited range of flexibility, next causing the prongs to enter and penetrate, then clenching the tips *p* thereof and finally 5 creasing and scoring-up as required in the making of boxes, and as appears in Figs. V and VI and IX. Fig. I is furthermore shown as applying reinforcement to a series of separate boards B which have been cut to 10 a specific size suited to some particular kind and shape of box. I would have it clearly understood that I do not limit myself in any way either to the kind of board material or to the manner in which it is supported or 15 moved along. Nor have I any reason to believe that the prior art whether merely practised or patented as well compels me to limit the scope of this application to any specific character of pronged reinforcing 20 member or the manner of its automatic application to the board material that may have been selected.

The preferred type of machine as I have constructed and successfully operated it 25 comprises three pairs of standards 1, 2 and 3 supported in an elevated position in any suitable manner thereby and a feed table 4 having its advanced end beveled underneath at 5 near the standard 3. Another table 6 30 is supported in some feasible manner beyond the standard 3 and has that end which is nearest the same likewise beveled at 7. Supported in an inclined position between the standards 2 and 3 is another feed table 35 8 provided above with three longitudinally extending and equispaced channels 9 one of which is clearly shown in Fig. XI. The forward lower end of the table 8 is also beveled at 10 near the beveled end 5 toward 40 which such table converges to leave however a space therebetween of sufficient size for the passage of the boards B. The latter are caused to move along the table 4 by means of a pair of feed rollers 11 adjacent the 45 standard 1 and another pair of feed rollers each designated as 12 and adjacent the standard 2. The distance between the rollers 11 and the rollers 12 is such that a particular board is always fed along by either 50 one or the other in a well known manner. The upper ends of the pair of standards 1 are fashioned as bearings suited to support the shaft 13 of a large roller 14 upon which three rollers 14 are mounted. Each of these 55 rollers has wound upon it an indefinite length of metal strips M commonly known as strap-iron. Inasmuch as the subsequent use which is made of each of the three strips is identical the singular number will 60 hereinafter be employed in describing the course followed by any one thereof. Consonantly, the singular number of such other duplicated parts of the machine as perform successive operations upon or in the handling of the strips M will be employed. 65

The standards 2 support in a suitable upright guide-way a journal box 15 in which the shaft 16 of a rotary member 17 having a series of peripheral dies 18 moves. The conformation of these dies is clearly seen in 70 Fig. IV. Superposed above the journal box 15 is another journal box 19 which receives the shaft 20 of a rotary member 21 having peripherally projecting punches 22 which are similarly spaced as the dies 18 and 75 adapted to project therein as appears in both Figs. I and IV. The elevation of the journal box 19 may be adjusted by means of a manually operable screw 23 which passes through a top cross bar 24 and supports such box. This punch and die mechanism is adapted to strike-out the prongs P of the shape seen in Fig. XI, and progressively so, along the strips M by a continuous and positive action which may be 80 presumed.

The standards 3 likewise support in suitable guide-ways a journal box 25 adapted to mount the shaft 26 of a plain metal roller 27 the uppermost surface of which is substantially level with the top of the tables 4 and 6. Higher up the standards 3 similarly support a journal box 28 adapted to mount the shaft 29 of another metal roller 30 the lowermost surface of which is to be spaced a 90 distance from the roller 27 corresponding to the combined thicknesses of the particular board material B and the reinforcing member M which have been selected. The control of the spacing between the rollers 27 and 30 is similarly accomplished by means of a screw 31 passing through a bar 32 and adapted to carry the journal box 28. It is of importance to notice the arrows which indicate the direction of rotation of the rollers 27 and 30. Any feasible power connection for driving the rollers 27 and 30 will answer and therefore need not be and has not been shown. Beyond the standards 3 in a position below and above the table 6 are opposed male and female creasing rollers 33^a and 33^b respectively which are purposed to impart creases to the finished product in the flat along the four lines *b*³ in the board and the superimposed four lines *m*³ across the strips, preparatory to scoring-up along such creased lines. 105

The operation of the machine is as follows: The speed of travel of the boards B and the reinforcing member M having been 110 adjusted to correspond to the strip M as it is unrolled and drawn forwardly between the punch and die is subject to the operation of having pointed prongs struck-out at intervals along the middle thereof. Thereafter it passes downwardly along the table 8 the prongs P in the mean time moving through the channels 9 to converge toward the most advanced of the boards B. The tips *p* of the prongs will begin to penetrate 115 120 125 130

and enter the board some little distance prior to passage between the narrowest space between the rollers 27 and 30 as clearly appears in Fig. III. Thereafter the 5 prongs progressively penetrate along their own length through the board B to be finally bent backwardly or clenched against the under surface of the board at the narrowest point. The completion of such final affixing 10 operation is likewise clearly seen in Fig. III and is the more effectively accomplished owing to the rotation of the roller 27 in opposition to the direction of travel of the stock. An inspection of Figs. VII and 15 VIII which have been copied from my earlier application filed March 8, 1915, Serial Number 12,887, discloses the appearance of board material reinforced by a continuous metal strip having integral prongs penetrating 20 therefrom and clenched thereagainst by machine operation. In this connection mention is made that Figs. V and IX are also copied from the same application just identified and are again shown in 25 this application in order to reemphasize the manufacturing objects and practical utility of the subject matter of this application.

The modification to which Fig. X has reference resides in the omission from the 30 machine of the male and female die mechanism for first fashioning the prongs upon the metal reinforcing member of whatever shape. According to this modification a pair of standards 34 suitably support at 35 their upper ends a shaft 35 of a roller 36 upon which is wound a reinforcing member which has already had prongs struck-out therefrom. Such pronged member M is thereafter similarly conducted along the 40 same table 8 and otherwise handled as has already been described. It will be noticed also that the board material b is in this view shown to be a continuous piece of material. In this connection it may be well to reiterate 45 that the successful practice of my in-

vention is not limited to board material of any fixed range in thickness nor need there be in all cases a clenching operation following upon a compressive action because the tips p of the prongs need not necessarily project through boards of considerable thickness. It was with the preceding in view also that Fig. XIII has been added to this application; the further to test the feasibility of having the different kind of reinforcing member m which is mainly rectangular in shape and also includes a longitudinally extending connecting portion n' and a plurality of crosswise connecting portions n². The prongs have been designated as p'. 50

It should be understood that the term "board" as used in this application refers to and may mean any kind of material including fiber board and straw board, corrugated paper, of whatsoever width, length, thickness or area. 55

I claim:

1. The method of reinforcing a fiber board, which consists in presenting thereto a pronged metal member while both the 70 board and member are under tension such that the prongs of the member project toward the board, and exerting a compressive force to cause the prongs to become clenched in stretched relation upon the board, whereby to effect a continuously smooth, taut and permanent application of each to the other. 75

2. The method of reinforcing a flexible fiber box blank, which consists in progressively applying integral prongs of a metal 80 member in stretched continuity along said board while both blank and member are maintained under tension, causing the prongs to penetrate and become clenched to said blank, and finally creasing said board 85 and strip together whereby uniformly to span both locally.

Signed by me, this 15th day of September, 1915.

JOHN N. HAHN.
